(57) CLAIM

The ornamental design for a decorative stitching for a pocket, as shown and described.

DESCRIPTION

FIG. 1 is a front elevational view of a decorative stitching for a pocket showing my new design;

FIG. 2 is a right side elevational view thereof; and,

FIG. 3 is a left side elevational view thereof.

The broken line showing of the clothing pocket is for illustrative purposes only and forms no part of the claimed design.
